UNITED STATES PATENT OFFICE.

CHARLES H. SHARP, OF LOCKPORT, NEW YORK.

DESIGN FOR A CUSPIDOR ATTACHMENT.

SPECIFICATION forming part of Design No. 26,511, dated January 12, 1897.

Application filed December 10, 1896. Serial No. 615,217. Term of patent 7 years.

To all whom it may concern:

Be it known that I, CHARLES H. SHARP, a citizen of the United States, residing at Lockport, in the county of Niagara and State of New York, have invented and produced a certain new and original Design for Attachments for Dentists' Cuspidors; and I do declare the following to be a full, clear, and exact description of the invention, such as will enable others skilled in the art to which it appertains to make and use the same.

My invention has relation to a design for an attachment for dentists' cuspidors. It relates to the entire configuration of the attachment.

My invention relates particularly to the design for an attachment for dentists' cuspidors as illustrated in the accompanying drawings, in which—

Figure 1 is a perspective view of an attachment for cuspidors embodying my design. Fig. 2 is a top plan view, and Fig. 3 is a side elevation of the same.

The leading features of my design appear in the following description:

1 represents a plane arm having a serrated end 2, and its opposite end is bent back upon itself to form the elbow 3. The approxi-

mately parallel arm 4 terminates in a curved lip 5, which is then bent reversely upon itself to form the curved arm 6 to the bead 7, from which point it extends downwardly to form the extended crescent-shaped clamp 8.

The attachment is to be detachably secured to the projecting rim of a dentist's cuspidor, and is used to conveniently detach and remove the cotton pellets from the end of the carriers while at work, the pellet being caught by the bottom face of the teeth on the serrated edge, and when detached, in the act of drawing the instrument upwardly, the disengaged pellet falls by gravity into the cuspidor.

Having thus fully described my design, what I claim as new, and desire to secure by Letters Patent of the United States, is—

The design for an attachment for dentists' cuspidors, substantially as herein shown and described.

In testimony whereof I hereunto affix my signature in presence of two witnesses.

CHARLES H. SHARP.
